UNITED STATES PATENT OFFICE.

MATTHEW C. SHARPNECK, OF BOSTON, MASSACHUSETTS, ASSIGNOR TO THE AMERICAN PEAT MACHINERY COMPANY, OF PORTLAND, MAINE, A CORPORATION OF MAINE.

PEAT-MACHINE.

No. 858,353.

Specification of Letters Patent.

Patented June 25, 1907.

Application filed December 28, 1906. Serial No. 349,916.

To all whom it may concern:

Be it known that I, MATTHEW C. SHARPNECK, a citizen of the United States, residing at the city of Boston, in the county of Suffolk and State of Massachusetts, have invented new and useful Improvements in Peat-Machines, of which the following is a specification.

The improvements of this invention, more especially, are designed and intended for application to, and in combination so as to act in coöperation with a machine for preparing peat, or such like, for fuel, etc., and which machine is adapted, or constructed and arranged to form and compress the peat, etc., and to permit of its discharge, as so formed and compressed, continuously therefrom. As an illustration of such a machine, reference is hereby had to an application for United States Letters Patent, filed by me, October 13, 1906, Serial Number 338,871.

The improvements of this invention, especially and substantially, consist of two arrangements of mechanism, the one to sever the aforesaid formed and compressed peat, etc., into separate blocks or cakes, and to positively discharge such blocks or cakes therefrom to the other mechanism, which is to receive them as they are so discharged, and then to convey and deliver them regularly to a kiln, or other suitable apparatus, or means to dry them, and while either of said two mechanisms, of itself, and broadly considered, is susceptible of use independently of the other, yet, preferably, and under this invention, and for the best and most efficient results, and which constitutes also a feature thereof, said two mechanisms are constructed and arranged, each of itself, and combined with each other, and so that the mechanism to which the separate blocks or cakes are delivered and by which they are to be conveyed to the kiln, etc., will be directly and positively actuated from the mechanism provided to receive the peat, etc., from the forming and compressing machine therefor, and to sever and deliver it as aforesaid.

Further than the above, this invention embraces an arrangement of the severing mechanism so that it will be actuated directly from the force or pressure exerted by the formed or compressed peat, as it is continuously discharged from the machine in which it was formed and compressed, assist-

ed by the gravity of the separated blocks or cakes being carried by it.

In the accompanying drawings, forming a part of this specification, is illustrated the special features of this invention, and in a most efficient and practical form, both as to construction and as to arrangement of the several parts for fully carrying out the same.

Figures 1, 2, 3, 4 and 5 pertain, most particularly, to the mechanism for receiving the formed and compressed peat as it is discharged from the machine which formed and compressed it, and by which, it is positively severed into blocks or cakes, and delivered to the mechanism to convey it to a kiln, etc. Figs. 6, 7 and 8 pertain, particularly, to the mechanism for receiving the blocks or cakes from said severing mechanism, Figs. 1 to 5, both inclusive, and for conveying them to a drying-kiln, or other such like apparatus.

Fig. 1 is a side elevation of the mechanism to which it and Figs. 2 to 5, both inclusive, belong as aforesaid, broken away in some parts, and similarly showing, in side elevation, but broken away, the part, to wit, the discharge-spout of a peat forming and compressing machine, such as that to which this invention pertains. Fig. 2 is a transverse vertical section, dotted line 2—2, Fig. 1. Figs. 3, 4 and 5 are views, in detail, as hereinafter appear; Fig. 5 being on an enlarged scale, and a part plan view. Fig. 6 is a side elevation of the mechanism provided to receive the separated blocks or cakes from the mechanism of Figs. 1 to 5, both inclusive, and to convey the same to a drying-kiln, or such like. Fig. 7 is a horizontal section, in detail, and on an enlarged scale, heavy dotted line 7—7, Fig. 6. Fig. 8 is a transverse vertical section on an enlarged scale, heavy dotted line 8—8, Fig. 6.

In the drawings, A is the discharge-spout for the peat formed and compressed in a machine suitable therefor, and for one illustration of which reference is hereby had, as before stated, to the application aforesaid. The severing and other mechanisms of this invention, however, are shown as suitably constructed and arranged, and will be so described, for handling or manipulating two sections or lengths of formed and compressed peat as it, the peat, is delivered from said discharge-spout A, which is stationary and horizontal.

B is a vertical wheel-frame, consisting, as shown, of three annular or ring-plates, severally parallel with each other, and having a corresponding open space between each of the outer and side annular-plates and the intermediate annular ring-plate and this intermediate plate is midway between said two side-plates. Each side-plate of the frame B is fixed to the outer end-portions of a series of radial and equi-distant rods C, a separate series for each plate, and these two series of radial-rods C, at their inner ends, are severally and respectively fixed to similar hubs D, which are free to turn on a common horizontal stationary shaft E, fixed, at its opposite ends, in suitable parallel stationary and suitably supported standards or uprights F, shown as broken off Figs. 1 and 2. The intermediate plate, at its inner edge, is fixed to the outer or side-plates by a series of narrow parallel horizontal cross-bars G, and also by other cross-bars L severally arranged at equidistances apart and at distances corresponding to those of and in substantially the same planes as the radial-rods C and they, the cross-bars G and L, are severally in each instance, at a corresponding distance from the axial line of the wheel. In a radial line with each of said cross-bars G are similar radial-bars H on the inner face of each of the side-plates, and on both faces of the middle-plate of the wheel-frame B. Thus, it will be seen that the wheel-frame B, composed of side and middle annular-plates, &c., as described, is a frame free to rotate in a vertical plane on the fixed shaft E, and that, about said shaft and between its side and middle plates, all is practically free and open and there is no obstruction save that of said cross and radial-bars G, L and H, and further, that it has, as it were, two similar parallel compartments or spaces, each continuous throughout the whole of its periphery and each of which is closed only on its opposite vertical sides; and again, that because of the intervening cross-bars G and radial bars H, each of said compartments or spaces of the wheel-frame, has, as it were, a series of similar divisions, in pairs, side by side, and equi-distant from the axis of the wheel-frame, and that the boundaries of each of said divisions consist, in substance, of the closed vertical parallel sides of the side and middle-plates of which the wheel-frame is formed, and the vertical side edges of said cross and said radial-bars G and H, respectively. As the wheel-frame B is illustrated, it has twelve of said divisions on each side of its middle-plate. Each wheel-division, aforesaid, has an unattached bottom-plate J that fits its aforesaid boundaries and, when this bottom is in its innermost position, it rests at one end on a cross-bar G, at one end of such division, and fits about the two radial bars H thereat, see Fig. 5, more particularly. These several bottoms J are

separate and distinct from each other, and they are severally arranged for movement outward from and inward toward the axis of the wheel-frame B, and to be so moved, the two of each pair of them, which are in a corresponding transverse plane of the wheel-frame, are arranged to move as one, and for this movement of each pair, each of its members and at its central portion is similarly fixed to a radial rod of similar radial-frames K, which, said rods, are arranged to move as one through guide-ways of the horizontal cross-bars L, before referred to, attached to the side and middle-plates of the wheel-frame, and the inner ends of these frames K are in suitable operative connection with similar continuous cam-grooves M of vertical and parallel disks N rigidly fixed by their respective hubs to the shaft E. The shape of each of these cam-grooves M is the same, and it is as shown, full lines, Fig. 4, and dotted lines, Fig. 1, and that is such as will effect or secure an inward and outward movement of said bottoms J, as and for the purposes and otherwise as will hereinafter appear. The bottoms J are shown in dotted lines, Fig. 5, which as before stated is a plan view of the wheel-frame B at a part only thereof, and as if said part had a straight and not a curving outer outline or edge.

O, O are a series of radially arranged blades, each having its outer edge suitably adapted to cut or sever peat as hereinafter appears. There is a separate cutting-blade O for each division of the wheel-frame B, and, as to each division, its blade moves in and is guided at its opposite side-edges in corresponding radial-grooves a of the side-walls thereof, and it is arranged so that in such movements it will pass in close contact with the side vertical edges of said cross and radial bars G and H, and as will more fully hereinafter appear. Every pair of the cutting-blades O, in a corresponding transverse plane of the wheel-frame, are joined together at their inner edge b, (see Fig. 2), so as to move as one, and for their aforesaid movement their outer vertical edges are in suitable operative connection with similar continuous cam-grooves Q of parallel vertical disks R rigidly fixed by their respective hubs to the shaft E. The shape of these cam-grooves Q is shown, full lines, Fig. 4, and dotted lines, Fig. 1, and it is such as will effect or secure an inward and outward movement of said cutting-blades for the purposes and otherwise as will hereinafter appear.

Each pair of cutting-blades O has an ear-piece S, at its opposite vertical edges, suitably shaped to engage the radial-rods C, before referred to, and this engagement serves as a support, and a steadier and a guide to the cutting-blades in their aforesaid movement under the action of the cam-grooves Q thereon.

The wheel-frame and its several connections and parts, all as above described, constitute, in substance, the improvements of this invention which pertain to severing the 5 formed and compressed peat into blocks, or cakes, and for conveying and delivering them therefrom, and for its operation to that end, it is placed relatively to the discharge-spout A before referred to, so that the peat, as it 10 issues from such spout, as before stated, will enter upon the wheel-frame B between its several side and middle-plates, and into the said two parallel compartments or spaces therebetween, and that the bottom or floor of 15 the spout is along a horizontal plane substantially tangential to the bottoms J of the two divisions of the wheel-frame B then in line with said spout, and these bottoms are then, not only at their innermost position as to the 20 periphery of the wheel-frame, but also at their highest plane above the axial line of the wheel-frame B.

Fig. 1 shows the discharge-spout A and wheel-frame in the positions just above stated. 25 The lower wall or floor of the spout A is centrally and lengthwise slotted as at f, dotted lines, Figs. 1 and 3, along its length to permit the middle-plate of the wheel-frame B to pass therethrough and across the discharge- 30 spout A as it, the wheel-frame, rotates, as will hereinafter appear. Again the side-plates of the wheel-frame B are at the outside of the opposite side-walls of the discharge-spout A, or, in other words, said spout 35 extends and is located between them, Fig. 3.

In the position of the wheel-frame B above described, the cam-grooves M and Q, respectively, are in the positions shown, full lines, Fig. 4, and dotted lines, Fig. 1, and 40 otherwise the bottoms J of and the cutting-blades O for the several divisions of the wheel-frame are in the relative positions, respectively as shown, in part, in full, and in part, in dotted lines, Fig. 1, and these several 45 positions are produced as to each bottom J, and each cutting-blade O, by the action thereon of their respective cam-grooves M and Q as the wheel-frame rotates on its shaft E, as will hereinafter appear. As a further 50 explanation each cam-groove Q, for moving the cutting-blades O, is shaped, so that for the greater part of the rotation of the wheel-frame, the blades will be at their outermost position, and there so held, and so that each 55 pair of blades will be moved into their innermost positions, at or just before the time the divisions of the wheel-frame to which they belong have come to the mouth of the discharge-spout A, when, by the then continued 60 rotation of the wheel-frame they will be moved and forced through the peat being discharged from the spout A to their outermost positions, thereby cutting off a portion of such peat and which, owing to the middle- 65 plate of the wheel-frame, is then in two

lengths, and so two blocks or cakes of peat are produced at one and the same stroke of a pair of the cutting-blades; and further so that such pair of the cutting-blades shall remain in their outermost positions, until they 70 are again retracted, or moved into their innermost position, as before stated, which movement does not begin to occur until such pair of cutting-blades reaches the points Q² of the cam-grooves, when it continues until 75 the points Q³ are reached, on which said blades then begin to move outwardly and so continue reaching their farthest outward position when the pair of blades reaches the points Q⁴ of the cam. Again, for further 80 illustration, each cam-groove M for moving the bottoms J of the several divisions of the wheel-frame B is shaped so that, for at least about one-half of the rotation of the wheel-frame, such of the bottoms as are then being 85 operated on by the portion M² of such cam-grooves, will be at their innermost positions, and so that for at least about one quarter of the rotation of the wheel-frame such bottoms as are then being operated on by the portions 90 M³ of the said cam-grooves will be gradually moved from their innermost position to their outermost position, and so that for, at least, about one quarter, or for the remainder, of the rotation of the wheel-frame such bottoms as are then being operated on by the portion M⁴ of said cam-grooves will be gradually moved from their outermost positions to their innermost positions. Both of said 95 cam-grooves M are similarly located relative 100 to the axis of rotation of the wheel-frame, and this location is such that the bottoms J of each division of the wheel-frame will be at their innermost position, when such division is in its highest horizontal plane, and at 105 their outermost position when such division is in its lowermost horizontal plane, and that the outward movement of the bottoms, in pairs, will be effected, as the divisions are passing downward from the mouth of the 110 discharge-spout A, and will be fully completed when such divisions have reached their lowermost horizontal positions, and that the then inward movement of each pair of bottoms will be effected as their divisions are 115 passing upwardly toward the mouth of the discharge-spout A, and will be fully completed, before the divisions again come into their highest horizontal plane as aforesaid. The several radial-rods C of the wheel- 120 frame B similarly extend beyond the outer edges of each side-plate of the wheel-frame and to these extensions, and in a coincident vertical plane with each side-plate, is rigidly attached a similar annular-plate B² and so as 125 to have, in each instance, between its inner edge and the outer edge of its corresponding side-plate, a similar annular open space B³ of sufficient width to freely admit a forward projecting and curvilinear resilient exten- 130

sion or tongue-piece A^2 of the upper wall of the mouth of the discharge-spout A beyond the mouth of said spout. This extension A^2 is shaped to extend or cross and to rest upon the outer edges of the several plates of the wheel-frame B and to cover at least more than the two adjoining pairs of the wheel-sections, then in advance, or in front of the mouth of the spout, Figs. 1, 2 and 3.

10 A^3 is an arm fixed on and extending horizontally along a portion of the length of, but above the tongue-projection A^2 of the spout A .

A^4 is a vertical adjustable screw located in the outer end-portion of the arm A^3 and arranged to be screwed in and out of such arm and thus, by so adjusting its bearing or pressure on the said tongue-extension A^2 of the spout A , to increase or decrease, as the case may be, the frictional bearing or rest of said tongue on the outer edges of the wheel-frame B and all for a purpose and operation upon the wheel-frame, as will hereinafter appear.

The outer edge of each annular plate B^2 of the wheel-frame B has a series of tooth-projections B^4 , at equal distances apart and correspondingly located on each plate. 1 is an endless-belt or carrier located below the wheel-frame B , and in the same vertical plane and of a corresponding width therewith. This carrier extends for some distance in opposite directions from the transverse vertical axial plane of the wheel-frame, and it inclines, from end to end, being the highest at its end at the right and the lowest at its end at the left of said wheel-frame, and at each end it passes around a similar transverse guide-roller 2, each journaled in the opposite parallel side-rails of a suitable supporting and stationary frame 3, and between said end guide-rollers 2, said frame 3 is provided, at equi-distant points, with similarly journaled guide-rollers 4 for supporting the endless-carrier at intermediate points of its lengths in its movement or travel. This endless-carrier 1, at and along its length and near each of its side edges, is provided with a row of similar sockets 5, at regular and equidistances apart, and a distance corresponding to that of the teeth B^4 , before referred to, of the wheel-frame B , and otherwise said sockets 5 are in vertical planes coincident with said teeth, and all so that as the wheel-frame rotates its said teeth will engage said sockets of the endless-carrier and cause the same to be moved lengthwise under the wheel-frame and in the direction of the arrows 6, the rotation of the wheel-frame being in the direction of the arrows 7, and all for a purpose as will hereinafter appear.

8, 8 are a series of raised and parallel transverse cleats, fixed, preferably, at regular distances apart on the outer surface of the endless-carrier 1, and which distances, in each instance, is to be such as to secure a co-op-

erative action thereof with corresponding raised transverse cleats 9 at the opposite end-portions of a series of similar flat wooden boards 10 of rectangular outline, Figs. 6, 7 and 8. The boards 10 are contained in a pile and each rests by its cleats 9 on the board next below. The lower board of the pile, is shown, at its opposite ends, as engaged with and supported on the teeth of the corresponding pairs of toothed-wheels 11, 75 which are suitably located therefor, and in each instance, these pairs of toothed-wheels are fixed to and carried by the outer end-portions of corresponding longitudinal shafts 12 which are journaled in suitable fixed bearing-blocks 13 of the supporting-frame 3, before referred to for the carrier 1 but are held from so turning and set free to turn all as and for a purpose as will be hereinafter described. Said pile of boards is at and above 85 the right-hand end-portion of the carrier 1 and each board, at its four corners, sets in similar vertical right-angular ways 14 of four fixed corner vertical posts 15, suitably located and supported therefor. 16 are vertical bevel gear-wheels on the end-portions of the shafts 12, carrying said toothed-wheels 11, situated toward and nearer to the wheel-frame B .

17 are vertical bevel gear-wheels, meshing 95 the bevel gear-wheels 16, and they, gears 17, are carried by a horizontal transverse shaft 18, which extends across, but is in a plane above the endless-carrier 1 and is journaled and free to turn at its opposite end portions in suitable fixed bearing-blocks 19 supported from the frame 3 for the endless-carrier 1.

20 is a vertical escape-wheel fixed on one end-portion of the transverse shaft 18, and 105 21 is a pallet-pawl located for its teeth to engage the teeth of the escape-wheel, and to operate thereon and therewith, all as well known in the escapement of watch and clock movements, that is to say, so as to allow on a swing or rock of the pallet in either direction an intermittent or step by step rotation of the escape-wheel in the direction of the arrow 22, and in this case at stated times relative to the rotation of the wheel-frame B , 110 and thus to allow of an intermittent or step by step rotation of the toothed-wheels 11 under the weight of the boards 10, but at all other times to hold the escape-wheel against rotation, and the same as to said toothed 120 wheels 11 and all as and for purposes as will hereinafter fully appear.

23 is the stationary fulcrum of the pallet 21. The free end-portion 24 of the pallet 23, that is, its end-portion opposite to its forked and toothed end, is situated in the vertical plane of a fixed horizontally projecting flange or rib 25, located on the outer vertical face of one of the annular-extensions B^2 of the wheel-frame B . This rib 25 is concentric 130

with the axis of, and, as shown, Figs. 1 and 6, it extends around the wheel-frame B for a little over one-half of its circumference, and its end 26, to wit, its forward end in relation 5 to the direction of the rotation of wheel-frame B, by abutting against the free end 24 of the pallet tilts or swings that end of the pallet downward and thus sets the escape-wheel free to rotate a given distance in the 10 direction of the arrow 22, on which the pallet and escape-wheel are held against change of their respective positions for the whole length of the rib 25 as the wheel-frame continues its rotation, by reason of the then bearing of the 15 end 24 of the pallet against the outer circular running face or edge 27 of said rib, when said end of the pallet escaping from said rib at its rearward end 28, the pallet is thereby freed and so it rocks or tilts back to its normal position, that is, its position in which it was before being tilted as aforesaid, and in this position the pallet remains holding the escape-wheel against further rotation until by the 20 continued rotation of the wheel-frame B said 25 forward end 26 of the rib 25 again contacts with the free end 24 of the pallet, when the pallet is again tilted, and so on as before.

The tilting of the pallet, as described, releases the escape-wheel for an intermittent, 30 or a step by step rotation, and in each instance it is produced by the weight of the boards 10 on the toothed wheels 11, acting on the escape-wheel through the intermediate shaft and gear-connection described and 35 thus on each step by step movement of the escape-wheel, the then lowest or underboard of the pile of boards 10 is freed to drop onto the endless-carrier 1 below it, followed by an engagement of the toothed wheels 11 with 40 the board which was next above said board so dropped, and therethrough all said boards are held suspended until the next movement of the escape-wheel as before and so on.

30 is an endless-carrier or belt, shown only 45 in part. This carrier 30 is similar to, and is designed to coöperate with the carrier 1, and it is supplementary to said carrier and leads, as shown, off from one end thereof, and from thence it is to pass to a drying kiln, or other 50 apparatus, suitable for drying pressed blocks of peat, and which apparatus is not shown.

The operations of the several mechanisms which have been now fully described and in detail, otherwise than as such operations 55 thereof have already been explained, and acting separately and co-operatively with and relatively with each other, it being understood that the formed and compressed peat to be handled by them comes out of or ex- 60 udes from the mouth of the discharge-spout A under a more or less forcible and appreciable pressure are, in substance, as follows:— The peat, passing from the spout A, is in two 65 separate continuous lengths, as and for the reason before stated, and it so enters into the

two adjoining divisions of the wheel-frame B then in the same horizontal plane with the spout and under and covered by its forward extension A² which covers also the next two adjoining divisions in advance thereof, and by this covering thereof, the peat is held 70 against escaping upwardly, it being otherwise confined in said divisions by their closed sides and bottoms. The peat so entered and as was before noted herein, presses forcibly 75 against the cutting-blades O in advance thereof and then in their outermost positions, as has been before explained, and consequently the wheel-frame B is forced forward, or in other words, it is caused to ro- 80 late, in the direction of the arrows 7, Figs. 1 and 7, while at the same time and which are traveling with the peat and the wheel-frame, the cutting-blades of said peat-charged divisions, and which were at their innermost po- 85 sitions and in the same vertical plane as the mouth of the spout when the peat first began to enter them, are made to move outwardly and across said peat and thus to sever or cut therefrom blocks or cakes, one for each division, and so on and in like manner and with like results with the successive or following 90 divisions of the wheel-frame, as it, the wheel-frame, continues its rotation under the forcible pressure of the continuous and constant 95 exuding or escaping lines of peat from the mouth of the spout A against the cutting blades which are outwardly presented to its said action, and all of which is successively followed, and by each pair of said divisions in 100 turn, that is, one pair after the other, by the discharge therefrom of the blocks or cakes of peat they separately contain when such divisions have reached their lowermost horizontal 105 positions, because of the outward movements of their separate bottoms J as has been before explained, and by the deposit of said so discharged blocks on a board 10 then being carried along under the wheel-frame, by the endless carrier 1, (said board not being 110 shown in the drawings) but which board has, during the mean time, dropped from the pile of boards onto such carrier in proper season, by the action of the escapement and connecting mechanism before explained. Said carrier 115 is under a continuous movement, in the direction of the arrows 6, produced by and through the meshing with its sockets 5 of the radial-pins or teeth B⁴ of the wheel-frame B. Thus, as a whole and in a thoroughly automatic and continuous manner, and as is obvious without further explanation, so long as the prepared peat is forced out of the discharge-spout A into sections of the wheel-frame B as described, the wheel-frame will be 120 rotated, the so discharged peat will be cut into separate blocks or cakes, and such cakes will be deposited on a board 10, on the carrier 1, and said carrier will be carrying such board so loaded with peat-blocks forward to 130

and delivering it to the endless belt 30, to be carried by it to a drying kiln (not shown) or other apparatus suitable for drying said blocks, it being understood that the carrying boards 10 for the peat-blocks are dropped onto the carrier 1, one after another, from the pile thereof and in proper and regular order by and through the operation of the escapement and connecting mechanism herein before particularly described, and particularly illustrated, Figs. 5, 6, 7 and 8 of the drawings, and which operation is effected or secured by the combined action of the projecting-flange 25 of the rotating wheel-frame B, the pallet 21, the escape-wheel 20, and the mechanism between the axle or shaft of said escape-wheel and the board holding or retaining toothed-wheels 11, all as before described.

20 Neither a drying kiln, nor any other apparatus or means for drying the peat-blocks, nor any means for transferring the boards 10, on which the peat-blocks have been deposited, from the endless-carrier 1 to such 25 kiln etc., constitute any part of this invention and therefore it is not deemed necessary to herein further describe or to particularly illustrate the same in the drawings.

The cleats on the boards 10 and on the 30 carrier 1, engage each other as the carrier travels along and thus a positive carrying of the boards is insured by the carrier.

The overlapping tongue-extension A² of the spout A, as has been before stated, holds 35 the peat in the sections of the wheel-frame B as it is being delivered to such sections from the spout, from upward escape and as the frictional pressure or bearing of this tongue-extension A² on the peripheries of the outer 40 and mid-annular plates of the wheel-frame B is capable of adjustment, as has been described, obviously, the rotation of the wheel-frame, under the pressure of the peat exuding from the mouth of the spout A, can be retarded as may be desired, and thus a greater or lesser compressing of the peat in the sections of the wheel-frame secured, it being 45 obvious, however, that as the mechanisms are arranged and combined and are operated, that, in any event there will be a more or less greater resistance to the discharge of the peat from the spout A, for the reason, that the movement and action of the several mechanisms are all obtained from the force 50 exerted in the original instance on the cutting-blades O which are in advance of the spout A and are in their outermost positions, as has been explained, assisted, to a more or less greater extent, by the gravity of the 55 peat-blocks contained in the sections of the wheel-frame that are between the highest and the lowest horizontal positions or planes thereof. Again the wheel-frame B while described and shown as having two parallel 60 vertical series of divisions may have only a

single vertical series of divisions without affecting in the least degree, or manner the operations of the mechanisms of this invention as they have been herein described, and again the wheel-frame B may have more than 70 two vertical series or divisions. Again it may be well to observe that the boards 10 follow one after another on their common carrier 1, and that for each rotation of the wheel-frame B there are two separate droppings of the boards from their common pile, and that each board in the course of its travel under the wheel-frame B receives the peat-blocks from six pairs of the twelve pairs of sections of said frame. 80

From the description herein given, in connection with the drawings, it is plainly obvious that the several mechanisms are actuated from the pressure of the peat, escaping from the spout A, on and against a cutting-blade or blades O of the wheel-frame B assisted by the weight of the peat-blocks in the sections, and again, as is apparent, all else being equal that the actions or movements of the several mechanisms must necessarily 90 be properly timed as to each other. Further, it is obvious, that the sections of the wheel-frame act as molds for the peat and in each the peat is or can be necessarily more or less compressed in its bulk and shaped thereto. 95 Further, it will be observed, that, while the mechanisms of this invention have been herein particularly described as applied to an apparatus for preparing peat, etc., for fuel such as is embraced in my said application for Letters Patent, it is not intended in any respect to limit the same in their application thereto or to any other special apparatus for preparing peat, etc., for fuel. 100

It is plain, and without departing from the 105 spirit of this invention, first, that the wheel-frame B may be adapted as well known, and for illustration, by connecting driving gear-wheels or driving-belt and pulley-wheels, or other suitable driving mechanism, so as to be 110 rotated independently of the action of the discharged peat from the spout A thereon; second, that the endless-carrier 1 may be adapted, as well known, as for illustration, by connecting driving gear-wheels or driving 115 belt and pulley-wheels, or any other suitable driving mechanism, so as to be rectilinearly moved as described, independently of the rotation of the wheel-frame B; and third, that the mechanism for holding and allowing the 120 boards 10 to drop one after another, as has been described, may be arranged and adapted for operation, by a suitably driven rotating device separate from the rotating wheel-frame B. But while these several changes 125 can be made and with good and practical success, yet, for obvious reasons, it is especially important and desirable to have the several mechanisms of this invention arranged separately and as one whole and 130

adapted and connected to be driven as has been herein particularly described, that is, by the action of the forcible pressure of the peat discharging from the spout A, or other discharge of a peat forming and compressing machine on a wheel-frame substantially such as has been shown and described and which is free to rotate under and because of such pressure, and thence, through such rotation of the wheel-frame to secure and cause the proper movements of the other mechanisms, such as the severing-blades O and bottoms J and endless-carrier 1 and the board-holding and releasing-devices, and all substantially such as shown and described.

It will be observed that in lieu of arranging the mechanism for the deposit on each board 10 carried by the endless-carrier, or on the carrier directly, of six separate blocks from 20 six sections of the wheel-frame in one and the same line of its divisions, said mechanism may be arranged for the deposit of a greater or lesser number than six blocks, by simply adapting the lateral projecting 25 flange or rib 25 of the wheel-frame B therefor, that is, by providing the wheel-frame with a number of separated parts of the flange of corresponding lengths as well as the open spaces between them, or again that the 30 separate parts of said flange and the open spaces between them may be of varying lengths relative to each other.

Having thus described my invention, what I claim and desire to secure by Letters Patent is,

1. The combination with the delivery spout, or other discharge of a machine, otherwise suitable to prepare peat, etc., for use as fuel, and to continuously deliver or discharge it therefrom, preferably, under a more or less forcible pressure, of a circular wheel-frame free to rotate and divided into separate equidistant sections, severally open at its perimeter and at said perimeter in position to receive in its said sections the peat as delivered or discharged, a series of peat cutting- or severing-blades and a series of movable-bottoms for said wheel-sections, severally free and separately adapted for radial 45 movement as to the axis of rotation of said wheel-frame, and means to so move said blades and said bottoms, adapted and arranged to be actuated from and by the rotation of said wheel, substantially as described, for the purposes specified.

2. The combination with the delivery spout, or other discharge of a machine otherwise suitable to prepare peat, etc., for use as fuel, and to continuously deliver or discharge it therefrom, preferably, under a more or less forcible pressure, of a circular wheel-frame free to rotate and divided into separate equidistant sections, severally open at its perimeter and at said perimeter in position to receive in its said sections the said peat as de-

livered or discharged, a series of peat cutting or severing-blades and a series of movable-bottoms for said wheel sections, severally free and separately adapted for radial movement as to the axis of rotation of said wheel-frame, means to so move said blades and said bottoms, adapted and arranged to be actuated from and by the rotation of said wheel, and a continuous rectilinear traveling endless-carrier, positioned as to said wheel-frame to receive from its said sections the blocks of peat contained therein and as they are discharged therefrom, substantially as described, for the purposes specified.

3. The combination with the delivery spout, or other discharge of a machine, otherwise suitable to prepare peat, etc., for use as fuel, and to continuously deliver or discharge it therefrom, preferably, under a more or less forcible pressure, of a circular wheel-frame 85 free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades 90 and said bottoms, adapted and arranged to be actuated from and by the rotation of said wheel, and a continuous rectilinear traveling endless-carrier, positioned as to said wheel-frame to receive from its said sections the blocks of peat contained therein and as they are discharged therefrom, and said carrier and said wheel-frame relatively adapted for the latter to actuate or drive the former, substantially as described, and for the purposes specified.

4. The combination with the delivery spout, or other discharge of a machine, otherwise suitable to prepare peat, etc., for use as fuel, and to continuously deliver or discharge it therefrom, preferably, under a more or less forcible pressure, of a circular wheel-frame 110 free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to receive from its said sections the blocks of peat contained therein and as they are discharged therefrom, and separate boards disposed lengthwise on and along said carrier,

one following the other in regular order, and between it and said wheel-frame, substantially as described, and for the purposes specified.

5. The combination with the delivery spout, or other discharge of a machine, otherwise suitable to prepare peat, etc., for use as fuel, and to continuously deliver or discharge it therefrom, preferably, under a more or less 10 forcible pressure, of a circular wheel-frame free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to 20 receive from its said sections the blocks of peat contained therein and as they are discharged therefrom, separate boards disposed lengthwise on and along said carrier, one following the other in regular order, and between it and said wheel-frame, and means to automatically deliver said boards one after another to said carrier and to dispose them along the length thereof in regular order, substantially as described, for the purposes 30 specified.

6. The combination with the delivery spout, or other discharge of a machine, otherwise suitable to prepare peat, etc., for use as fuel, and to continuously deliver or discharge 40 it therefrom, preferably, under a more or less forcible pressure, of a circular wheel-frame free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to 50 receive from its said sections the blocks of peat contained therein and as they are discharged therefrom, a pile of separate superimposed boards normally held above said carrier for being delivered one after another thereto and along the length thereof, and means adapted at regular times relative to the travel of said carrier to automatically free the lower board of said pile of boards, for it to drop onto said carrier, and at the same time to hold the boards of said 60 pile which were over and resting on it from dropping, and which said means and said wheel-frame are relatively adapted to each other to secure, from and under the rotation of the wheel-frame, an action of said means to permit the lower board of said pile of boards to drop and to hold the boards which were above it from dropping, all substantially as described, and for the purposes 70 specified.

7. The combination with the delivery spout, or other discharge of a machine, otherwise suitable to prepare peat, etc., for use as fuel, and to continuously deliver or discharge it therefrom, preferably, under a more or less 80 forcible pressure, of a circular wheel-frame free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to 90 receive from its said sections the blocks of peat contained therein and as they are discharged therefrom, a pile of separate superimposed boards normally held above said carrier for being delivered one after another thereto and along the length thereof, and means adapted at regular times relative to the travel of said carrier to automatically free the lower board of said pile of boards, for it to drop onto said carrier, and at the same time to hold the boards of said 100 pile which were over and resting on it from dropping, and which said means and said wheel-frame are relatively adapted to each other to secure, from and under the rotation of the wheel-frame, an action of said means to permit the lower board of said pile of boards to drop and to hold the boards which were above it from dropping, all substantially as described, and for the purposes 110 specified.

8. The combination with the delivery spout, or other discharge of a machine, otherwise suitable to prepare peat, etc., for use as fuel, and to continuously deliver or discharge it therefrom, preferably, under a more or less 120 forcible pressure, of a circular wheel-frame free to rotate and divided into separate equidistant sections, severally open at its perimeter and at said perimeter in position to receive in its said sections the peat as delivered or discharged, a forward extension of the upper side of said spout or discharge positioned and adapted to resiliently bear and press on and to extend across and cover a portion of the open perimeter of the wheel-frame, as it, the wheel-frame, passes from said discharge, a series of peat cutting or severing-blades and a series of movable-bottoms for said wheel-sections, severally free and separately adapted for radial movement 130

time to hold the boards of said pile which were over and resting on it from dropping, all substantially as described, and for the purposes specified.

7. The combination with the delivery 70 spout, or other discharge of a machine, otherwise suitable to prepare peat, etc., for use as fuel, and to continuously deliver or discharge it therefrom, preferably, under a more or less 75 forcible pressure, of a circular wheel-frame free to rotate and divided into separate equidistant sections, severally open at its perimeter and at said perimeter in position to receive in its said sections the said peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to 80 receive from its said sections the blocks of peat contained therein and as they are discharged therefrom, a pile of separate superimposed boards normally held above said carrier for being delivered one after another thereto and along the length thereof, and means adapted at regular times relative to the travel of said carrier to automatically free the lower board of said pile of boards, for it to drop onto said carrier, and at the same time to hold the boards of said 90 pile which were over and resting on it from dropping, and which said means and said wheel-frame are relatively adapted to each other to secure, from and under the rotation of the wheel-frame, an action of said means to permit the lower board of said pile of boards to drop and to hold the boards which were above it from dropping, all substantially as described, and for the purposes 100 specified.

8. The combination with the delivery spout, or other discharge of a machine, otherwise suitable to prepare peat, etc., for use as fuel, and to continuously deliver or discharge it therefrom, preferably, under a more or less 110 forcible pressure, of a circular wheel-frame free to rotate and divided into separate equidistant sections, severally open at its perimeter and at said perimeter in position to receive in its said sections the peat as delivered or discharged, a forward extension of the upper side of said spout or discharge positioned and adapted to resiliently bear and press on and to extend across and cover a portion of the open perimeter of the wheel-frame, as it, the wheel-frame, passes from said discharge, a series of peat cutting or severing-blades and a series of movable-bottoms for said wheel-sections, severally free and separately adapted for radial movement 120

as to the axis of rotation of said wheel-frame, and means to so move said blades and said bottoms, adapted and arranged to be actuated from and by the rotation of said wheel, substantially as described, for the purposes specified.

9. The combination with the delivery spout, or other discharge of a machine, otherwise suitable to prepare peat, etc., for use as fuel, and to continuously deliver or discharge it therefrom, preferably, under a more or less forcible pressure, of a circular wheel-frame free to rotate and divided into separate equi-distant sections, severally open at its perimeter and at said perimeter in position to receive in its said sections the peat as delivered or discharged, a forward extension of the upper side of said spout or discharge positioned and adapted to resiliently bear and press on and to extend across and cover a portion of the open perimeter of the wheel-frame, as it, the wheel-frame, passes forward from said discharge, means carried by said discharge and projecting therefrom over said forward extension thereof and adapted to adjust the bearing and pressure of said extension on the perimeter of the wheel-frame, a series of peat cutting or severing-blades and a series of movable-bottoms for said wheel-sections, severally free and separately adapted for radial movement as to the axis of rotation of said wheel-frame, and means to so move said blades and said bottoms, adapted and arranged to be actuated from and by the rotation of said wheel, substantially as described, for the purposes specified.

10. The combination with the delivery spout, or other discharge of a machine, otherwise suitable to prepare peat, etc., for use as fuel, and to continuously deliver or discharge it therefrom, preferably, under a more or less forcible pressure, of a circular wheel-frame arranged to rotate on a stationary axial shaft and divided into separate equi-distant sections severally open at its perimeter and at said perimeter in position to receive in its said sections the peat as delivered or discharged, a series of peat cutting or severing-blades and a series of movable-bottoms for said wheel-sections, severally free and separately adapted for radial movement as to the axis of rotation of said wheel-frame, and means, consisting of cam-acting disks fixed on said shaft, a separate cam for said blades and a separate cam for said bottoms, and connections between said cams and said blades and bottoms adapted and arranged to be operated by them as the wheel-frame rotates and thus to move said blades and bottoms in and out of said wheel-frame sections, and in determined radial lines

thereof, substantially as described for the purposes specified.

11. The combination with the delivery-spout, or other discharge of a machine, otherwise suitable to prepare peat, etc., for use as fuel, and to continuously deliver or discharge it therefrom, preferably, under a more or less forcible pressure, of a circular wheel-frame free to rotate and divided into separate equi-distant sections, severally open at its perimeter and at said perimeter in position to receive in its said sections the peat as delivered or discharged, a series of peat cutting or severing-blades and a series of movable-bottoms for said wheel-sections, severally free and separately adapted for radial movement as to the axis of rotation of said wheel-frame, means to so move said blades and said bottoms, adapted and arranged to be actuated from and by the rotation of said wheel, a continuous rectilinear traveling endless-carrier, positioned as to said wheel-frame to receive from its said sections the blocks of peat contained therein and as they are discharged therefrom, a pile of separate superimposed boards normally held above said carrier for being delivered, one after another, thereto and along the length thereof, and means consisting of a circular flange or rib fixed on and laterally projecting from one side of and extending partially around, and axially coincident with the axis of said wheel-frame, a pallet fulcrumed on a suitable support and adapted to be rocked in one direction and held against rocking by said flange or rib and escaping from said rib left free to rock in the opposite direction, an escape-wheel arranged to act in conjunction and co-operation with said pallet and having its shaft suitably journaled on a stationary support for the rotation thereof, a series of toothed-wheels carried by shafts journaled on suitable stationary supports and adapted and arranged to rotate and to engage by their teeth the lower board of said pile of boards, and therethrough to hold the pile against dropping while said toothed wheels are held from rotation, and gear-wheels, in part carried by the escape-wheel shaft and in part otherwise suitably carried and as a whole adapted to make connection between said toothed-wheels and said escape-wheel, all substantially as described, and for the purposes specified.

In witness whereof, I have hereunto set my hand in the presence of two subscribing witnesses.

MATTHEW C. SHARPNECK.
